UNITED STATES PATENT OFFICE

2,425,495

TWO-WAY TELEPHONE SYSTEM

Bertram A. Trevor and John B. Atwood, Riverhead, N. Y., assignors to Radio Corporation of America, a corporation of Delaware

Application October 30, 1943, Serial No. 508,354

11 Claims. (Cl. 250—13)

1

This invention relates to circuit arrangements for two-way telephone systems. A fundamental feature of the invention resides in the relay circuit arrangements for facilitating the conditioning of apparatus so that it will normally be held in a standby condition awaiting an outside call, and at other times, by means of a push button on a handset, the apparatus may be suitably conditioned for transmitting a message. In the standby condition no anode voltage is supplied to the transmitter, and hence there is no radiation therefrom.

It is an object of our invention to provide a novel circuit arrangement for a two-way radio telephone system.

It is a more specific object of our invention to provide relay-operated circuits whereby the necessary transfer of controls from receiver to transmitter and vice-versa is made possible by the actuation of a push button mounted on the telephone handset.

Other objects and advantages of our invention will become apparent in the following detailed description which is accompanied by a drawing, the sole figure of which represents a preferred embodiment.

Referring to the drawing, we show a handset 25 in which are included a microphone 1, an earphone 2, and a push button 3 for closing circuit contacts 26. The handset 25 is associated with a so-called call box which may be located at any suitable point more or less remote from the receiving and transmitting units 22 and 24 respectively. Another handset (not shown) may also be plugged into the circuit by means of two jacks 20a and 20b. In such a handset the microphone circuit would include a plug for insertion in the jack 20a, and the earphone would be plugged into the jack 20b. We preferably use a conventional double plug, the plug shanks being suitably spaced apart to fit into adjacent jacks.

The receiver 22 is maintained in a standby condition by means of a power supply 23. An independent power supply 9 is associated with the transmitter 24. Certain sections of this transmitter power supply are also maintained operative during standby conditions as well as during conversation. Thus the transmitter tube filaments may be continuously heated, if desired, and direct current may be obtained by rectification of a 60-cycle source, for use in biasing the tubes, and also for relay operation. Another section of the power supply 9 comprises a transformer 31 the primary of which is normally open-circuited and the secondary of which is connected

2

to a rectifier circuit for producing the anode voltage. Relay 7 has a contact *d* in circuit with the primary of transformer 31, so as to provide control of the transmitter output in dependence upon the pressing of the push button 3 on the handset. The push-button-to-relay circuit will presently be traced.

Three relays 4, 5, 7, and an antenna relay having coils 8 and 10 are preferably used. Their function will be described in the ensuing paragraphs covering the mode of operation.

An alarm system which may include a bell 30 is arranged to be actuated in response to the receipt of an incoming carrier wave. This carrier wave may be amplified and rectified by means not shown, but the derivative is preferably a direct current which is applied to the relay 5 for energizing the same. When relay 5 operates, it closes a circuit (to be more completely traced hereinafter) through relay 4 which operates an alarm circuit, the latter being either audible or visual. The alarm is here shown as a bell. Switch 21 is normally closed when the station is held in a standby condition but can be automatically opened during a telephone conversation in order to silence the alarm. Automatic operation is provided, as is conventional, by mounting the switch 21 in a cradle for the handset so that circuit closure depends upon the weight of the handset when resting on a push button.

Various other pieces of apparatus are also included in the system, an illustrative embodiment of which is herein shown. The coordination of functions of the several units will, however, be best understood by a full description of the mode of operation.

The handset and associated equipment comprised in a so-called "call box" may be located at a remote point with respect to the transmitter and receiver. The call box has associated with it a handset 25 consisting of the microphone 1, receiver 2, and push button 3. It also has a relay 4 which closes when a carrier is present in the receiver and operates an alarm circuit which may be a light, bell, or other indicator.

The circuits are drawn with the equipment in the receiving condition, but with no carrier being received. In this condition, the carrier-operated relay 5 short-circuits one half of the audio output transformer 6 of the receiver and acts as a partial squelch. This prevents excessive noise in the handset receiver when no signal is present. The handset receiver 2 is connected to the output transformer 6 through contacts *a* and *b* of

relay 7. The antenna circuit relay is held in the receiving position as shown by current from the negative section of the transmitter power supply 9 flowing through contacts *c* of relay 7, through the relay winding 10, and thence through resistors 11 and 12 to ground. The resistors 11 and 12 limit the current to a suitable value.

When the station is called from a remote point the incoming carrier wave is amplified and rectified. A rectification component causes relay 5 to be operated. This removes the short circuit from the audio output transformer 6 and applies a push-push voltage to the line from the receiver power supply 23 through current limiting resistor 13. Current flows through contacts *a* and *b* of relay 7, through the center-tapped choke 14, through the relay 4 to ground and back through ground to the receiver power supply. This current operates relay 4 for the purpose of actuating an alarm circuit. When the calling station shuts off its transmitter, these circuits return to the standby position.

To answer a call, the handset is lifted from its cradle, thus silencing the alarm. Then the microphone switch 3 on the handset is closed. The input transformer 15 has two primary windings and one secondary winding. Closure of the microphone switch 3 causes current to flow as follows: From the transmitter power supply to ground, through one primary winding of transformer 15 which is grounded, through switch 3, microphone 1, the other primary winding of transformer 15, the relay coil 7, resistor 11, relay winding 10, and contact *c* of relay 7 to the negative terminal of the power supply 9.

This causes relay 7 to operate, which disconnects the handset receiver 2 from the audio output transformer 6 and connects it across the microphone circuit through blocking condensers 16 and resistors 17. This is to supply sidetone, the resistors 17 being provided as means for setting the sidetone level.

Relay 7 also closes circuits through its contacts *c* and *d* for placing the transmitter in operation. The resistor-condenser combinations 27, 28 are merely spark suppressors on the relay contacts. Contact *c* feeds current through the antenna relay coil 8, thus connecting the antenna to the transmitter 24. While contacts of relay 7 are moving, there is a momentary opening of the D. C. circuit which would cause the circuits to return to the receiving position, where the circuit would be closed again and the process would repeat indefinitely, all the relays sounding like buzzers. This is overcome by the use of a large condenser 19. In the receiving condition it becomes charged, and during the momentary opening of the contacts it maintains the current flow for a sufficient length of time for the transfer to take place.

When the microphone switch 3 is opened, the circuits return to the receiving condition, and when a conversation has been completed, the standby condition is restored by restoring the handset to its cradle.

The parallel jacks 20a and 20b are for the purpose of providing operation from the transmitter-receiver location in addition to the remote operating position at the call box.

It will be understood by those skilled in the art that our invention is not restricted to the exact circuit arrangement herein shown and described by way of illustration. Nor is it essential that the components of the system be combined in the same manner as illustratively shown.

We claim:

1. In a two-way communication system, a radio transmitter including modulating means and a source of modulating waves, a radio receiver including a signal responsive device, an antenna common to the transmitter and the receiver, a relay for alternately connecting the antenna to the input side of the receiver and to the output side of the transmitter, a second relay for connecting a power supply to said transmitter and for causing the attenuation of response in said receiver during the operation of said transmitter, and means including a direct current source and a circuit for simultaneously actuating both said relays therefrom, said circuit including a push-button, switch-contacts of which are in series with said source of modulating waves, whereby the times for transmission are selected.

2. A system according to claim 1 and including an alarm device operable under control of an incoming carrier wave applied to said receiver for actuating an alarm.

3. A system according to claim 1 in which the first said relay possesses two alternatively energizable windings for effecting its switching operation.

4. A system according to claim 1 and including a transformer for intercoupling said source of modulating waves and said modulating means, said transformer having two primary windings which are in circuit with windings of said relays and with said direct current source.

5. In a two-way communication system, a radio transmitter, a radio receiver, a hand-set having a microphone for modulating the transmitter and an earphone for listening to the reception of signals by said receiver, a push button the contacts of which are in circuit with said microphone, relay means operable by said push button for conditioning said transmitter to modulate signals as originated at said microphone, an antenna normally connected to the input side of said receiver, and additional relay means in circuit with the first said relay means whereby said antenna is switched into connection with the output side of said transmitter during talking periods.

6. In a two-way radio telephone system, a transmitter having a power supply unit for intermittent use and a receiver having a power supply unit for substantially continuous use, call-responsive means operable upon reception by said receiver of a carrier wave signal initiated at a remote point, a microphone coupled to a modulator circuit in said transmitter, an earphone coupled to the output circuit of said receiver, an antenna circuit common to the transmitter and the receiver, relay means normally effective to maintain said antenna circuit connected to the input side of said receiver, a transfer relay operable to apply power to said transmitter from its power supply unit, also to open the receiver circuit through said earphone, and an operating circuit for said relay means and said transfer

65 relay comprising a push button, the impedance of said microphone, and actuating coils on said relay means and said transfer relay, the circuit last mentioned being effective to condition the system for talking and listening at mutually exclusive times.

7. In a two-way telephone system, a transmitter circuit including a microphone and a modulator, a receiver circuit including an earphone, means normally connecting the receiver 75 to the earphone while maintaining the micro-

phone and modulator inoperative, a "push-to-talk" key, relay means controlled by said key and having contacts for connecting the microphone to the modulator and other contacts whereby the transmitter circuit is conditioned to operate, and means controlled by said relay means for causing a component of the microphone output to be fed to the earphone.

8. In a system according to claim 7, a spark suppressor circuit having series resistance and capacitance in the last said means, said circuit being arranged to be closed by said relay means.

9. In a telephone system a radio receiver having means therein for amplifying and rectifying a component of the incoming carrier wave, a relay operated by said rectified component, a responsive device connected to receive the output from said receiver, and circuit means operative during standby periods for attenuating said output, thereby to suppress noise effects, said circuit means being subject to control by said relay for increasing the signal response level in said responsive device during the reception of a message.

10. In a two-way communication system, a single antenna for radio transmission and reception, a transmitter having modulating means controllable by a local source of signals, a receiver having responsive means controllable by a remote source of signals, relay means normally set to feed the remote signals from said antenna to said receiver, said relay means being operable to switch the antenna connection from said receiver to said transmitter, an alarm relay operable upon reception of signals from the remote source, an indicator controlled by said alarm relay,

means for holding said indicator in a standby condition during receipt of said remote signals, said means being manually operable to disconnect the indicator from the receiver during use of said system for two-way communication, and means independent of the last said means whereby modulated output signals are caused to be fed from said transmitter to said antenna, said relay means being simultaneously effective to render said receiver unresponsive.

11. A system according to claim 10 and including means operable simultaneously with said alarm relay for increasing the response level of said receiver to a value above that which is normally maintained during standby periods.
